CONTAINER FOR THREAD BODIES

Paul Plunkett, Port Chester, N. Y., assignor, by
mesne assignments, to Moulded Pulp Corpora-
tion, Dover, Del., a corporation of Delaware

Application January 27, 1934, Serial No. 708,668

9 Claims. (Cl. 206—1)

This invention relates to individual containers for thread bodies, and more especially for rayon thread bodies which are to be shipped from one point to another.

In the manufacture of rayon, it is often necessary to transport thread bodies for considerable distances when the thread is still in a damp condition. It is highly important that the moisture content of the thread body be maintained as nearly uniform and constant as possible during such shipment. If, for example, the surface layers of a thread body are allowed to dry out while the inner layers are still moist, the uniformity of quality of the thread in the body is lost and considerable waste of thread results.

The present invention provides individual moisture-proof containers for rayon thread bodies, these containers being suitably shaped to receive a thread body and to hold the thread body centered therein so as to avoid contact of the yarn with the wall of the container. It is an object of the invention to provide a container which is light in weight and can be made so inexpensively that it can be economically thrown away after being once used. This saves the trouble and expense of returning empty containers to the point of origin.

According to the invention, I provide containers of paper pulp molded to ultimate shape, each container consisting of a receptacle and a cover which overlaps to enclose a space adapted to accommodate a thread body wound on a cop or other suitable core. The top and bottom of the container are centrally molded so as to form elements which frictionally engage and center the extremities of the cop on which the thread body is wound. The receptacle and cover are preferably impregnated with moisture-resistant materials so that a substantially moisture-proof package is obtained.

Various other advantageous details of structure will be apparent to one skilled in the art from the description of certain embodiments of the invention which follows and from the disclosure thereon on the drawing, of which

Figure 1 is a sectional view of an embodiment of the invention.

Figures 2, 3, 4 and 5 are similar views of various modified forms of the invention.

Figure 6 is a fragmentary sectional view of a further modification.

As shown in Figure 1, the container may consist of a receptacle 10 which is comparatively shallow. A relatively deep cover 11 is provided for the receptacle 10, the lower marginal por-

tion 12 of the cover being adapted to overlap the upper marginal portion 13 of the receptacle 10. If desired, the portion 13 may be inwardly offset as at 14 so that the marginal portion 12 of the cover can make a flush joint with the receptacle 10. The bottom of the receptacle is molded to form an upwardly projecting hollow boss 20, this boss being of suitable diameter to enter and fit frictionally within the lower end of a thread cop 21 on which may be wound a thread body 22. This centers the lower end of the thread body so that a thread body may readily be correctly located within a receptacle 10 so as to receive the cover 11 thereover. As shown, the cover may have its top molded to form a downwardly, i. e. inwardly, projecting ring 25, this ring defining a central dome 26 which projects upwardly and is of such diameter as to receive with a frictional fit the upper end portion of the thread cop 21 when the cop is seated on the boss 20 and the cover 11 is placed in position on the receptacle 10. Thus both extremities of the cop 21 are engaged and held in correct centered position by the boss 20 and the ring 25. In addition to frictional engagement between the faces of the overlapping portions 12 and 13, I may employ a suitable adhesive or fastening elements to hold the cover on the receptacle. To seal and strengthen the joint between the receptacle and its cover, I may pass a sealing strip 27 around the container so as to cover the joint. This sealing strip may be of paper or of any other suitable material and is preferably applied with an adhesive.

Figure 2 illustrates a slightly modified form of the invention. The receptacle member 10 may be similar to that illustrated in Figure 1. The cover member 30 is, however, molded with a downwardly or inwardly projecting boss 31 adapted to enter the open top of a thread cop 21, 40 thread cops of this type being frequently used for rayon thread bodies. In other respects, the container may be similar to that shown in Figure 1.

Figure 3 shows another form of cover for a container embodying the invention, this cover having a more deeply molded ring 35 than the ring 25 illustrated in Figure 1, and having a central dome 36 adapted to receive and center the upper end portion of a thread cop 37 of the 50 type having a closed apex. In other respects, the container may be similar to that illustrated in Figure 1.

Figure 4 shows a container, the top of which is molded with a downward or inward projection 55

40, this projection being provided with an aperture 41 through which the upper end portion of a thread cop 37 may project. In a container 5 of this type, it is important that the edges of the aperture 41 fit tightly against the wall of the cop 37 so as to prevent the escape of moisture at the line of junction. If desired, some waterproofing material such as melted paraffin wax may be applied to the hollow formed by the projection 40 so as to seal the line of junction between the sides of the aperture 41 and the wall of the cop 37 which is in contact therewith.

Figure 5 shows a cover having a boss 50 projecting upwardly from the plane of the top of the 15 cover. This boss, being hollow, may be shaped to receive and fit the upper end portion of a thread cop 21. The receptacle may be molded with a central boss having a portion 51 adapted to receive the lower end portion of the cop 21 20 in fitted engagement, and an upper portion 52 which may be of lesser diameter so as to receive the top boss 50 of a similar container in a stack.

Figure 6 shows a receptacle having an inwardly 25 dished circumferential ring 60 in the side wall thereof near the rim, i. e. in the inner offset portion 13 of the side wall. The cover member also has an inwardly dished ring 61 near its lower edge, adapted to fit into the groove formed by the ring 60, so that, when the cover is pushed 30 down into place on the receptacle, the ring 61 snaps into the groove 60, and thus the cover is resiliently held in place as well as by frictional engagement between the overlapping portions. If desired, additional securing means, such as 35 an adhesive, fastening elements or a sealing strip 27, may be employed to strengthen the joint.

It is obvious that various other modifications and details of structure may be employed without departing from the spirit or scope of the invention as defined in the following claims.

I claim:—

1. A container for a thread body, comprising a shallow receptacle and a deep cover of paper pulp molded to ultimate shape and moisture resistant, said receptacle having a central boss projecting upward to engage and center the lower end of a conical thread cop, said receptacle having the central portion of its top molded to engage and to center the upper end portion of a 50 cop seated on said boss.

2. A container for a thread body, comprising a shallow receptacle and a deep cover of paper pulp molded to ultimate shape and moisture resistant, said receptacle and cover each having 55 an inwardly projecting portion adapted to engage and to center a thread cop within the container and overlapping marginal portions forming a flush joint, and a sealing strip secured around the side wall of said container to cover 60 said joint.

3. A container for a thread cop, comprising a shallow receptacle having a central boss projecting upwardly from the bottom thereof to receive and fit into the lower end of a conical thread cop, 65 and a cover for said receptacle having its top shaped with a downwardly projecting central ring adapted to engage and fit over the upper end portion of a thread cop seated on said boss.

4. A container for a thread cop, comprising a 70 shallow receptacle made of paper pulp molded to ultimate shape and provided with a central

boss projecting upwardly from the bottom thereof to receive and frictionally fit the bottom portion of a thread cop, a molded paper pulp cover of substantially greater height than the receptacle, said cover having an upwardly converging side wall the lower portion of which overlaps the rim portion of the receptacle, said cover having a downwardly projecting ring formed in the top thereof to engage and to center the upper end portion of a thread cop seated on said boss. 10

5. A container for a thread body, comprising a receptacle and a cover therefor, said receptacle being of paper pulp molded with a central raised boss adapted to fit frictionally into the lower end of a rayon cop, said cover being of paper pulp 15 molded with a lower edge portion adapted to overlap the rim of said receptacle and a top molded to engage frictionally the upper end portion of a rayon cop when the cop is seated on said boss and the cover is in position on said receptacle.

6. A container for a thread body, comprising a receptacle and cover of paper pulp molded to ultimate shape and moisture resistant, said receptacle having an upstanding side wall and a 25 raised central boss adapted to receive and frictionally fit into the lower end of a thread cop, said cover having an upwardly converging side wall the marginal portion of which overlaps and fits snugly against the rim portion of said receptacle, and a top shaped to engage and to center the upper end portion of a thread cop seated on said boss. 30

7. A container for a thread body, comprising a receptacle and cover of paper pulp molded to 35 ultimate shape and treated with moisture-resistant material, said receptacle having a central boss adapted to receive and fit into the lower end of a thread cop and a side wall with the rim portion thereof offset inwardly, said cover 40 having an upwardly converging side wall of substantially greater height than that of the receptacle, the lower marginal portion of the cover being shaped to fit frictionally on the offset portion of the receptacle to form a flush joint therewith, said cover having its top shaped to engage and to center a thread cop seated on said boss, and a sealing strip secured about said container and covering said joint. 45

8. A container for a thread body, comprising a 50 shallow receptacle and a deep cover of paper pulp molded to ultimate shape and moisture resistant, said receptacle and cover having overlapping marginal portions constructed for both frictional and resilient resistance to separating forces, said 55 receptacle and cover having central inwardly projecting means for engaging and centering a thread cop within said container.

9. A container for a thread body, comprising a shallow receptacle of molded paper pulp with 60 a central hollow boss projecting upwardly and adapted to engage within the lower end of a thread cop, and a comparatively deep cover adapted to overlap the rim portion of the receptacle and to extend upwardly therefrom, said 65 cover having a central molded boss in the top thereof projecting upwardly to receive the upper portion of a thread cop and to enter the bottom boss of a similar container stacked thereon.

PAUL PLUNKETT.
